(57) **CLAIM**

The ornamental design for a button of a shaving razor handle, as shown and described.

DESCRIPTION

FIG. 1 is a first perspective view of a button for a shaving razor handle of the present invention;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof; and,

FIG. 8 is a second perspective view thereof.

The broken line disclosure of the razor handle illustrates the environment of the claimed design. The broken line disclosure on the button illustrates a portion of the claimed design. Neither of the broken line disclosures form part of the claimed design.
